Primary Examiner—Cathy Anne MacCormac*Assistant Examiner*—Melanie Levy(74) *Attorney, Agent, or Firm*—Jeffrey M. Kaden; Gottlieb, Rackman & Reisman, P.C.(57) **CLAIM**

The ornamental design for an earring, as shown and described.

DESCRIPTION

FIG. 1 is a front elevational view of an earring showing my new design;

FIG. 2 is a top elevational view thereof;

FIG. 3 is a side elevational view thereof;

FIG. 4 is a rear elevational view thereof; and,

FIG. 5 is a bottom elevational view thereof.

The broken lines are for illustrative purposes only and form no part of the claimed design.
